UNITED STATES PATENT OFFICE.

OSCAR J. APPEL, OF PATERSON, NEW JERSEY.

HEADLIGHT.

Application filed March 16, 1926. Serial No. 95,106.

This invention relates to headlights and more particularly to headlights designed for automobiles, an object of the invention being to provide an improved shape and construction of reflector and lens which will give full road illumination but will prevent glare.

A further object is to provide a headlight of this character in which the lens projects forwardly from the reflector so as to give lateral illumination and also to permit the headlight to be observed by cars approaching at an angle thereto.

A further object is to provide a headlight of this character which will be of simple and inexpensive construction, strong and durable in use, and which will most efficiently perform the functions for which it is intended.

With these and other objects in view, the invention consists in certain novel features of construction and combinations and arrangements of parts which will be more fully hereinafter described and pointed out in the claim.

In the accompanying drawings—

Figure 1 is a view in longitudinal section, illustrating my improved headlight;

Figure 2 is a view in horizontal section on the line 2—2 of Figure 1;

Figure 3 is a view, in front elevation, of the headlight.

A represents the reflector and B the lens of my improved headlight. The reflector A may constitute a casing or it may be enclosed within a casing, as may be desired.

The upper half of the reflector A is parabolic in horizontal section, as shown in Figure 2, and semi-parabolic in vertical section, as shown in Figure 1. The lower half of the reflector at the rear thereof is of general concave shape forming in effect a depression 1, and a lamp 2 is located in a socket 3 at the rear of the reflector and positioned properly with relation to the several reflecting surfaces to perform the functions more fully hereinafter pointed out.

The front wall of the depression 1, constituting the concave reflector, merges into a horizontal flat surface 4 located slightly below the vertical centre of the headlight. At the forward edge of the portion 4 a downwardly and forwardly inclined flat surface 5 is provided which merges into the transversely circular wall of the reflector. This

surface 5 is preferably dulled in any approved manner so that it is not a full or direct reflector of light. The forward end of the reflector has a ring 6 secured thereto and this ring supports the lens B.

I would call particular attention to the shape of this lens B, which is of general cylindrical form projecting forwardly an appreciable distance and having a convexly closed forward end 6. The upper half of this lens B is frosted or otherwise rendered translucent, as shown at 7, while the lower half is clear, as indicated at 9.

The meeting edges of the concave reflector 1 and the inclined non-reflecting surface 5 constitute a wall or bridge, indicated at 8, which is in a plane sufficiently high to prevent any direct rays of the light from the lamp 2 from passing through the clear portion 9 of the lens. In other words, the rays of light are prevented from forming a horizontal bolt of light but are all directed downwardly by reason of the several reflecting surfaces above described. Hence, the downwardly directed rays through the lower clear portion 9 of the lens give a full road illumination, and the frosted upper surface of the lens, combined with the fact that none of the rays of light are inclined upwardly, prevents any possibility of glare.

Furthermore, the inclined dulled surface 5 of the reflector gives to the headlight the general appearance of having a completely dulled or translucent surface. In other words, the optical effect when a person looks directly into the lens is that he sees the translucent portion 7 in the upper portion of the lens and the dulled surface 5 gives him the impression that the whole front of the lens is translucent.

By reason of the fact that the lens is projected forward an appreciable distance, lateral illumination is had and also automobiles approaching at an angle can see the headlights and accidents will be prevented.

I do not wish to be limited to the exact material, shape, size and proportions of my improved headlight but desire to cover the general arrangement, and hence various slight changes and alterations might be made in the general form of the parts described without departing from my invention and therefore I do not limit myself to the precise details set forth but consider myself at liberty to make such slight changes and

alterations as fairly fall within the spirit and scope of the appended claim.

I claim:

A headlight, comprising a reflector, the upper half of which is parabolic in horizontal section and semi-parabolic in vertical section, the lower portion of the reflector at the rear thereof is depressed forming a convex reflector merging into a substantially

horizontal flat surface at its forward edge, 10 and said reflector at the forward edge of the flat surface having a forwardly and downwardly inclined dulled portion, and a forwardly projecting lens secured to the front of the reflector and translucent throughout 15 the upper portion thereof.

OSCAR J. APPEL.
